UNITED STATES PATENT OFFICE.

TAZEWELL GILMER, OF NEW YORK, N. Y.

METAL BENDING AND STRAIGHTENING APPARATUS.

No. 826,239.

Specification of Letters Patent.

Patented July 17, 1906.

Application filed February 14, 1906. Serial No. 300,974.

To all whom it may concern:

Be it known that I, TAZEWELL GILMER, a citizen of the United States, and a resident of the city of New York, borough of Brooklyn, county of Kings, and State of New York, have invented a new and useful Improvement in Metal Bending and Straightening Apparatus, of which the following is a description.

The object of my invention is to provide a machine of this class that will straighten any form of metal bar or tube and do this without injury even to the thinnest tube. This object is accomplished by my invention, one embodiment of which is hereinafter disclosed.

For a more particular description of my invention reference is to be had to the accompanying drawings, in which—

Figure 1 is a plan view of my improved machine, and Fig. 2 is a side elevation of the same.

Throughout both views of the drawings similar reference characters designate similar parts.

The frame 1 of my machine is given any convenient form and is provided with suitable supports 2. The bed 3 is made sufficiently rigid to withstand without bending all the stresses incident to its use.

Power to run the machine is derived through a belt 4, pulley 5, and shaft 6, on which said pulley 5 is mounted. The shaft 6 is suitably mounted in the bed 3, also carries a smaller pulley 7, a spur-gear 8, and a bevel-gear 9. The pulley 7 carries a belt 10, which also passes over a pulley 11 at the other end of the machine, which pulley 11 is on a short shaft 12, suitably mounted in the bed 3, and which also carries a pinion 13 and bevel-gear 14, similar to the gears 8 and 9, respectively. The bevel-gear 14 meshes with a corresponding gear 15, which has a vertical shaft 16 mounted in the bed 3 and which carries at its upper end a feed-roller 17, which in the present instance is shown suitable for tubing which is circular in cross-section. This is also true of the other rollers herein shown, and so will not be further referred to, as it is obvious that these rollers are always given a shape to correspond to the cross-section of the metal fed to them and straightened by the machine. Opposite the roller 17 is an identical one 18, mounted loosely on a stud-shaft 19, fixed in the bed 3. Should a more positive action be required, the roller 8 could be mounted to move through gears with the roller 7, a statement equally true of all feed-rollers in

this case, in which only one of each pair is shown as positively driven, because the construction is somewhat simplified for the purposes of illustration. It is obvious that both 60 in each pair may be positively driven, if desired. The spur-gear 13 meshes with a similar gear 19^a on a horizontal shaft 20, which passes through a bearing 21, projecting upwardly from the bed 3, and preferably is integral therewith, and this shaft 20 carries a roller 22, which is identical with the rollers 17 and 18. A stud-shaft 23 in the bearing 21 carries a second roller 24 opposite and identical with the roller 22, but loosely mounted, as 70 is the roller 18. The rollers 17 and 18 may be called the "vertical" feed-rollers and the rollers 22 and 24 the "horizontal" feed-rollers. As the feed-rollers and their mountings at the other end of the machine are identical in all respects with those just above described, it is sufficient to say that the vertical rollers 21 are driven from the bevel-gear 9 and the horizontal rollers 26 are driven by the gear 8.

The straightening-rollers of this machine 80 may also be divided into two sets and designated, as the feed-rollers, as "horizontal" and "vertical." The vertical rollers 27 are each loosely mounted on stud-shafts 28, fixed in guide-plates 29, which move laterally of the 85 machine and horizontally in guides 30, preferably integral with the bed 3. Three sets of these rollers 27 are shown, which is the preferable number, although more or less may be employed, and each of the plates 29 is provided with a vertical and downwardly-extending stud 31, which rests in the slotted end of a horizontal lever 32. These levers 32 are pivoted at 33 between the studs 31. Springs 34, resting against the ends of the 90 center plate 29 and also against lugs 35, tend to hold the plates 29 and their rollers 27 true and in symmetrical relation to the axis of the machine, so that a straight bar or tube would pass freely through the machine. The 95 horizontal straightening-rollers 36 are similarly mounted on studs 37, fixed in vertically-movable plates 38, sliding in guides 39, preferably integral with the bed 3, and these plates 38 have at their upper ends horizontally-disposed studs 40, connected by levers 41, fulcrumed at 42, all substantially similar to the levers 32 and their mounting, as above described. Coiled springs 43 rest under the vertical plates 38 and hold the same true. Should more springs be desired, they may be added. As above shown and described, the

levers 32 and 41 are pivoted about midway of their lengths; but this is not necessary or even desirable for certain classes of work which must be bent back upon itself more than it is out of alignment. In such a case the pivots 33 and 42 should be correspondingly shifted to permit this action, and so are adjustably mounted with slots 44 in the levers 32 and 45 in the standards 39, whereby this adjustment can readily be made. This adjustment may be made by any suitable means, one form only being shown.

From the foregoing, the operation of my improved machine will be readily understood. When a bent bar or tube is fed into the machine by the rollers 17 and 18, it passes through the rollers 22 and 24, all of which feed, but do not tend to straighten, the bar. The bar then passes on to the first set of straightening-rollers 27, which immediately move laterally of the bed 3 of the machine according to the amount and direction of the bend in the bar or tube. The slide 29 of these rollers readily permits this; but as the first plate 29 assumes a new position the levers 32 cause the other plates 29 to move correspondingly against the action of the springs 34, so that the middle plate 29 is shifted a proportional distance laterally, but 25 in the opposite direction, and the third or end plate 29 is shifted an equal distance in the same direction as the first plate 29. The bar or tube would then pass through the first rollers 27 and perhaps the second set 27 without being straightened, but by simply moving on in the direction of its curvature; but even if the second set of rollers 27 did not tend to straighten the bar the third set 27 would bend it back upon itself an amount 30 proportional to what it would be out of true between the first two sets of rollers 27, so that it would be bent true, and as the bar or tube straightened in the machine the position of the rollers 27 would be correspondingly changed, so that the bar or tube would finally emerge through the feed-rollers 25 and 26 in a straight condition if the bends were all in one plane; but as such bends are 35 found to be infrequent in practice it is necessary to have between the vertical rollers 27

the horizontal rollers 36, mounted in a similar manner and which act in the same way, except in a vertical instead of a horizontal plane. The result of the simultaneous action of these rollers 27 and 36 is a compound one which will straighten out any curve in any direction provided the bar or tube is not too much bent to pass the feed-rollers when entering into the machine. If the bend is too great to be taken out when 40 passing through the machine once, it may be passed through twice or more or through several machines in tandem or through one machine with more than one set of each of the straightening-rollers.

The precise embodiment of my invention is not material provided its essential characteristics are employed as pointed out in the annexed claims.

What I claim is—

1. In a machine of the class described, feeding-rollers, straightening-rollers arranged in pairs, means for causing some of said pairs to move simultaneously transversely of the axis of the machine and not all in the same 75 direction.
2. In a machine of the class described, feeding-rollers, straightening-rollers mounted in pairs, means for causing one set of pairs to move simultaneously and transversely of the machine in a horizontal plane.
3. In a machine of the class described, feeding-rollers, straightening-rollers mounted in pairs, means for causing one set of pairs to move simultaneously and transversely of the 85 machine and in a vertical plane.
4. In a machine of the class described, feeding-rollers, straightening-rollers mounted in pairs means to cause one set of pairs to move simultaneously and transversely of the 90 machine in a horizontal plane and means for causing another set of said pairs to move simultaneously and transversely of the machine in a vertical plane.

Signed this 7th day of February, 1906. 95

TAZEWELL GILMER.
